UNITED STATES PATENT OFFICE.

GRANVILLE A. HUMASON, OF HOUSTON, TEXAS.

PUMP.

Application filed October 27, 1923. Serial No. 671,039.

This invention relates to new and useful improvements in a pump.

One object of the invention is to provide a pump of the character described specially designed for the purpose of pumping fluids from wells, and embodying means whereby a lubricant may be supplied when necessary between the traveling valve and the standing barrel.

10 Another object of the invention is to provide a pump including a surrounding jacket, a standing barrel therein, and a plunger arranged to work within the barrel, said pump also having a lubricant retainer around said barrel with ports through which the lubricant may be supplied to the interior of said barrel, and packing on opposite sides of said retainer between said barrel and jacket.

20 A still further feature of the invention resides in the provision of a pump of the character described, embodying means for adjusting said packing.

25 The lubricating system herein shown and described is also suitable for use in pumps of various designs, as well as in other forms of mechanism embodying relatively movable parts.

30 With the above and other objects in view, this invention has particular relation to certain novel features of construction, operation and arrangement of parts, an example of which is given in this specification and illustrated in the accompanying drawings, wherein:

35 Figure 1 shows a sectional view of the upper section of the pump.

Figure 2 shows a sectional view of the middle section thereof.

40 Figure 3 shows a sectional view of the lower end of the pump.

Figure 4 shows a transverse sectional view of the pump taken on the line 4—4 of Figure 1.

45 Figure 5 shows a transverse sectional view taken on the line 5—5 of Figure 2; and,

Figure 6 shows a vertical sectional view of the jacket showing a side elevation of the barrel therein.

50 Referring now more particularly to the drawings, wherein like numerals of reference designate similar parts in each of the figures, the numeral 1 designates a surrounding tubular jacket whose lower end is internally threaded to receive the upper end of

55 the tubular valve casing 2. The upper end

of the tubing 3 is threaded into the lower end of the casing 2, and this tubing usually carries the well screen (not shown).

Within the lower end of the casing 2 there is the valve seat 4 above which is the ball valve 5, provided to control said seat, and confined within the valve cage 6; said seat, valve and cage constituting what is commonly known as the standing valve of

the pump.

The working barrel consists of a series of glands and intervening packing sleeves. The lower gland is designated by the numeral 7, and is sleeve-like in form, having the external annular flange 8 at its upper end, which rests on the internal annular shoulder 9, formed within the lower end of the jacket. The upper gland is indicated by the numeral 10, and fits within the upper internally threaded end of the jacket, and has its upper end enlarged into an externally threaded head 11, which is screwed into said upper end of said jacket. The fluid conduit pipe 12 has its lower end threaded into the upper end of the jacket.

Between said glands 7 and 10 are the packing sleeves 13 and the perforated sleeve-like glands 14.

Within the working barrel, above described, there is the plunger 15. This plunger is tubular and the passageway through it is controlled at its upper and lower ends by the ball lift valves 16 and 17, confined within suitable cages 18 and 19, respectively. The cage 18 has the upwardly diverging ports 20, 21, and to the upper end of said cage, the lower end of the sucker rod 22 is attached. The plunger is reciprocated up and down in the usual way through this sucker rod. The cage 18, and consequently the sucker rod 22, has a swiveling connection with the plunger. In order to provide this swiveling connection there is a tubular thimble 23 whose lower end is threaded into the upper end of the body of the plunger and the upper end of this thimble has an external annular flange 24, forming a head. Surrounding this thimble and fitted loosely between the flange 24, and the upper end of the plunger body there is a gland 25 whose lower end has an external annular flange 26. There is a tubular nipple 27 whose lower end is threaded onto the gland 25, said nipple fitting loosely over the head 24 and having an internal annular shoulder 28 which

fits against the upper end of said head 22. The upper end of the nipple 25 is reduced and threaded up into the cage 17, and serves to connect the nipple to said cage as well as to clamp the valve seat 27 of the valve 15, in place.

It may be here stated that the head 11 of the gland 10 has a swiveling connection with said gland, and the upper end of said head has a polygonal socket 28, provided to receive a correspondingly shaped external enlargement 29, formed on the nipple 25 intermediate its ends.

Each of the glands 13 are sleeve-like in form, each having the external, annular end flanges, 30, 30, which fit closely within the jacket 1, forming the lubricant chambers 31 which are filled with a suitable lubricant, as hard oil or grease. These chambers are filled through the inlet ports 32, and are drained of waste through the outlet ports 33, said ports leading through said jacket at the upper and lower ends of the said chambers 31, respectively, and being normally closed by the removable plugs 34 and 35, respectively. The glands 13 are perforated, as shown to permit the lubricant to work through between the plunger and standing barrel for lubricating the same. While oil is being pumped, the oil itself will usually work its way in between the plunger and the pump barrel and sufficiently lubricate the pump, but if the well is dry, or if the oil should stop flowing, the lubricant in the chambers 31 will then lubricate the pump as above explained.

The lubricating system described may also be employed for lubricating cylinders of any character, having a traveling piston,

or plunger therein, and for all similar purposes.

In case the packing 12 becomes worn, permitting it to leak, the sucker rod may be lowered to seat the enlargement 29 in the socket 28, and then turned to screw the head 45 11 downwardly in the jacket, and all of said packings thus sufficiently expanded to form the required fit, or in case the packing is expanded too much, the sucker rod may be reversed to unscrew said head 11 and thus relieve the packing.

It is apparent that various modifications and applications of the construction herein described may be made without departing from the principle of the invention, and I hereby reserve the right to make such mechanical changes and adaptations as may be comprehended within the scope of the appended claim.

What I claim is:

A deep well pump including a jacket having a lower internal abutment, a barrel formed of alternately arranged cylinders and packing sleeves and resting on said abutment, a plunger in the barrel, some of said cylinders being formed with annular outside flanges spaced apart to form a lubricant chamber between them, said cylinders having lubricant ports leading from said chambers to the interior of the cylinder and said jacket having an upper and a lower port communicating with some of said chambers, and a removable upper abutment in the jacket abutting the upper end of the barrel.

In testimony whereof I have signed my name.

GRANVILLE A. HUMASON.
